UNITED STATES PATENT OFFICE.

HOMER C. SNOOK, OF CYNWYD, AND GEORGE H. WHITE, OF HAVERFORD, PENNSYLVANIA.

X-RAY APPARATUS.

1,252,504.

Specification of Letters Patent.

Patented Jan. 8, 1918.

Application filed May 26, 1915. Serial No. 30,509.

To all whom it may concern:

Be it known that we, HOMER C. SNOOK and GEORGE H. WHITE, citizens of the United States, residing at Cynwyd and Haverford, 5 counties of Montgomery and Delaware, respectively, State of Pennsylvania, have invented new and useful Improvements in X-Ray Apparatus, of which the following is a specification.

- 10 Our invention relates to a system for supplying to an X-ray tube or other translating device high potential uni-directional energy derived from alternating current or unidirectional current impulses.
- 15 Our invention resides in such a system which is applicable for producing a uni-directional impulse of high intensity in the consumption circuit, as for X-ray fluoroscopic purposes, for each semi-cycle of the 20 alternating current or for each wave or semi-cycle of one sign only; and also for delivering to the consumption circuit, particularly when including an X-ray tube, uni-directional impulses of lesser intensity.
- 25 Our invention resides also in such a system where all of the waves or semi-cycles of alternating current of one sign are suppressed or where waves or semi-cycles of both signs are used, and a portion only of 30 the waves or semi-cycles of one sign or both signs is employed, and particularly when substantially the last half of said waves or semi-cycles of one sign or both signs is used for producing the uni-directional impulses 35 of great intensity in the consumption circuit. And our invention resides further in such means coöperating with a synchronously rotating switch which coöperates in suppressing from the consumption circuit 40 any current impulses of improper direction resulting from the use of such portion, generally the last half, of such waves or semi-cycles of one sign or of both signs.

Our invention resides in the system and 45 apparatus hereinafter described and claimed.

For an illustration of one of the forms our invention may take reference is to be had in the accompanying drawing, in which:

Figure 1 is a diagrammatic view illustrating circuits and apparatus embodying our 50 invention.

Figs. 2 and 2^a are representations of an alternating current explanatory of our invention.

Fig. 3 is an end elevational view of a form 55 of commutator or contactor.

Fig. 4 is a side elevational view of the same.

Referring to Fig. 1, 1 and 2 represent the conductors supplying direct current to a direct current motor M coupled to an alternating current generator G. Or M may represent the direct current side of an inverted rotary converter whose alternating current side is represented by G. The device G may be a synchronous alternating current motor, in which case the direct current motor M is omitted, and the synchronous motor will drive the hereinafter described apparatus in synchronism with the alternating current. 70

In the conductor 1 is arranged a motor starting rheostat 3. The generator G or the alternating current side of an inverted rotary G delivers alternating current to the conductors 4 and 5 communicating with the reversing switch 6 from one of whose terminals extend the conductor 7 to one terminal of the primary P of a step-up transformer whose secondary is S. The other terminal of the reversing switch 6 connects by 75 conductor 8 with the adjustable resistance 9 connected to the switch 10 adapted to engage any of the contacts 11 to 15 inclusive. The contact 11 communicates through conductor 16 with a brush 17 of a commutator 18 or rotary contactor 18 whose other brush 19 communicates through conductor 20 with a tap in the primary P. The contacts 12 to 15 inclusive communicate respectively with different taps in the primary P. 80

The commutator 18 is secured upon the shaft 21 of the motor generator, inverted rotary, or synchronous motor. The shaft 21, when the dynamo-electric machine has four poles, makes one complete revolution for two 95 complete cycles of the alternating current.

The commutator 18 comprises the four conducting arcs or segments 22, 23, 24 and 25, of which 22 and 23 are electrically connected by conductor 26 and insulated from segments 24 and 25 which are connected together by conductor 27. 100

As shown, the commutator 18 is connected in series in the alternating current circuit including a part of the primary P of the step-up transformer. The brushes 17 and 19 are disposed at substantially 90 degrees from each other circumferentially of the 105

- commutator 18, and the segments 22 to 25 inclusive are in the example illustrated of such length as to correspond with substantially one half of one wave or semi-cycle 5 of alternating current, the commutator 18 being secured in such angular position upon the shaft 21 with respect to the brushes that the alternating current circuit through the commutator 18 is closed at approximately 10 the maximum 28, Fig. 2, of an alternating electro-motive-force wave and broken at substantially the zero point 29, the dotted portions of Fig. 2 indicating the parts of the electro-motive-force waves which are 15 not used. Fig. 2 therefore indicates that all the semi-cycles or waves of one sign, those below the line, are not used, and that the last half of each of the waves or semi-cycles of opposite sign only is used. 20 In Figs. 3 and 4 a form of commutator 18 is illustrated in greater detail. It is shown secured in fixed relation to the shaft 21 by a pin 30, Fig. 4. In addition to the contact segments mentioned, there are between 25 neighboring segments the four pairs of metallic segments 31 and 32 insulated from each other and from the segments 22 to 25 inclusive by the insulation 33, the segments 31 and 32 serving to avoid wear caused by 30 the brushes 17 and 19 which would otherwise occur if the entire space between neighboring contact segments were filled entirely by insulation, the insulation 33 between segments 31 and 32 of each pair assisting 35 further in preventing the jumping of arcs to a distance from the brushes.
- The brushes 17 and 19 are relatively thin as measured circumferentially of the commutator, and are preferably of laminated 40 copper or the like and supported by the brush holders 34, here shown as of the Baylis type.
- A coupling 35, Fig. 1, couples the shaft 36 of the rectifying switch E to the shaft 21 45 in any suitable angular relation for maintaining any desired angular relation between the commutator 18 and the rotating parts of the switch E.
- The switch E may be of any suitable construction or type and in the example illustrated is similar to that disclosed in Letters Patent of the United States No. 954,056 to H. C. Snook. The switch E comprises the stationary arcs 37 to 40 inclusive, of which 50 37 and 38 are connected to the terminal 41 of the secondary S and of which 39 and 40 are connected to the terminal 42 of the secondary S. Opposed to these arcs are the arcs 43 to 46 inclusive, of which 43 and 46 55 are connected by conductor 47 with the anode of the X-ray tube X, and of which 44 and 45 are connected by conductor 48 through ammeter 49 with the cathode or negative terminal of the tube X.
- 60 65 Coöoperating with the arcs are the cross

connectors 50, 51, 52 and 53 rotated by the shaft 36, the cross connectors 50 and 52 being disposed parallel with each other and at right angles to the cross connectors 51 and 53.

70

F represents in edge view a fluoroscopic screen between which and the target t of the tube X is disposed the object O which is to be examined.

The operation is as follows:

75

With the switch 10 in the position illustrated in Fig. 1, alternating electro-motive-force is impressed by device G upon the primary circuit through commutator 18 including that part of the primary P having 80 small number of turns or convolutions.

As the commutator 18 and switch E are rotated in synchronism with the alternating current in the primary circuit, the commutator 18 suppresses all of the waves or 85 semi-cycles of one sign and closes the circuit through the primary P at or near the maximum 28 of the electro-motive-force waves or semi-cycles of opposite sign, whereby uni-directional current flows 90 through the primary P until the zero or substantially zero point 29 is reached, when the commutator 18 again interrupts or breaks the primary circuit.

Since the primary circuit is closed at substantially the maximum of an electro-motive-force wave, there is a sudden rush of current through the primary P, which results in a peaked wave or impulse of high intensity in the secondary S, and during its 100 existence the cross connectors 51 and 53 are in coöperation with arcs 38, 44 and 40, 46, respectively, so that a current impulse of high intensity may be passed through the tube from arc 46 to arc 44, the terminal 42 105 of the secondary S during the existence of this peaked current impulse being positive, and the terminal 41 negative.

It would be expected that during the decrease in strength of the primary impulse 110 from its maximum to zero there would be in the secondary circuit a succeeding impulse of opposite sign to that of the impulse of high intensity passed through the tube X. But by the time the current impulse of 115 high intensity in the secondary has reached zero or substantially zero value, the cross connectors 51 and 53 will have rotated to a position beyond the arcs 38, 44, and 40, 46, to such position that the succeeding electro-motive-force wave in the secondary circuit will not soon enough attain a voltage high enough to cause current to leap the then lengthened air gap.

In the position illustrated in Fig. 1 the 125 primary circuit has just been closed, as at point 28, Fig. 2, and the cross connectors 51 and 53 have traversed half of the distance at which they coöperate with the arcs 38, 44 and 40, 46. By the time the segments 24 130

and 25 are leaving brushes 19 and 17, that is, after rotation of substantially 45 mechanical or 90 electrical degrees, the cross connectors 51 and 53 will have rotated 5 through a like number of degrees, and the angular extent of the arcs may be such that for such new position of the cross connectors there will be a substantial air gap between those cross connectors and the arcs, 10 and so offering too great a resistance to the second electro-motive-force wave in the secondary circuit to allow passage of current thereover, which current, if allowed to pass, would be in the wrong direction for the X-ray tube.

However, the angular extent of the arcs of the switch E is substantially that described in said prior Patent 954,056 for purposes of rectification to direct energy from 20 semi-cycles of both signs through the X-ray tube. And when of such extent the switch E will operate as above described in connection with the commutator 18.

Only cross connectors 51 and 53 are utilized when commutator 18 is operative, to suppress all semi-cycles of one sign, the cross connectors 50 and 52 being idle.

When it is desired to use energy from the waves or semi-cycles of both signs, the 30 segments 22, 23, 24 and 25 of commutator 18 may all be electrically connected as by electrically connecting the conductors 26 and 27. Then, as represented in Fig. 2^a, the primary circuit will be closed during substantially the last half of the waves or semi-cycles of both signs, circuit closure for the wave of one sign being indicated between the points 28 and 29, as in Fig. 2, and for the waves of opposite sign between points 35 55 and 56. When so using energy from the waves or semi-cycles of both signs all the cross connectors 50 to 53 inclusive, of switch E, are utilized, cross connectors 50 and 52 now coming into use in addition to the cross 40 connectors 51 and 53 for the purposes above given.

It will be noted that when the commutator 18 is in circuit as indicated in Fig. 1, the 50 number of turns in the primary P utilized is less than for any of the other positions of the switch 10. The use of such relatively smaller number of turns of the primary P results in the delivery by the secondary S of higher potential.

55 When the switch 10 is moved into engagement with any of the contacts 12 to 15 inclusive, a greater number of turns of the primary P are utilized, and in such case the commutator 18 is out of circuit and there is 60 passed through the primary P an alternating current, all the positive and negative waves or semi-cycles being utilized. In such case the switch E delivers uni-directional current to the tube X, as described in the 65 prior Patent 954,056.

In place of the shaft 21 being that of the motor generator of the inverted rotary converter, it may be the shaft of a synchronous motor driven by a source of alternating current, the motor serving to rotate the shafts 70 21 and 36, and the alternating current from the source being directly led to the conductors 7 and 8.

If the commutator 18 should be so disposed that the primary circuit is closed at 75 or substantially zero of an electro-motive-force wave and accordingly broken at or near the maximum of such wave, there will be serious sparking at the commutator 18 because of the rupture of the current at the 80 peak of the wave. By our preferred arrangement however, as illustrated, the circuit is closed at or near the maximum of the wave, and the closure of a circuit is accomplished with little or no sparking, and 85 the circuit is then broken at substantially the zero value, where again the sparking is negligible.

For fluoroscopic purposes high intensity 90 impulses of short duration may be employed. High voltage impressed upon the X-ray tube produces rays of great penetrating power. And due to the persistence of vision the current impulses through the tube need not succeed each other closely. However, 95 when the source of alternating current is one of 60 cycles per second, by the apparatus hereinbefore described when commutator 18 is in circuit, the tube X will receive 60 impulses per second. If considerably fewer 100 impulses per second are impressed upon the tube X they will occur at so great intervals that the persistence of vision will not suffice to maintain the effects upon the eye, and there will be observed a flickering effect. 105

What we claim is:

1. The combination with a source of alternating current, of a commutator driven in synchronism with the alternating current, said commutator comprising a pair of segments electrically connected to each other, insulation between said segments, a pair of brushes with respect to which said segments and insulation rotate, a transformer, an X-ray tube in the secondary circuit of said transformer, a connection from one of said brushes to a point in the primary winding of said transformer and the other of said brushes connected to a switch, and connections from said transformer primary and 110 said switch to said source of current. 115

2. The combination with a source of alternating current, of a commutator driven in synchronism with the alternating current, a transformer, an X-ray tube connected in 120 the secondary circuit of said transformer, a pair of brushes bearing on said commutator and connected respectively with the primary of said transformer and with a 125 switch, and connections from said trans- 130

former primary and said switch to said source of current.

3. The combination with a source of alternating current, of a commutator and a rectifying switch driven in synchronism with said current, a transformer, a translating device, said commutator and a switch intervening between the primary of said transformer and said source, said switch in one position connecting said commutator in series with a portion of the transformer primary, and in another position cutting out said commutator and cutting in a different number of turns of said primary.

15 4. The combination with a source of alternating current, of a commutator and a rectifying switch driven in synchronism with said current, a transformer, an X-ray tube, said commutator and a switch intervening between the primary of said transformer and said source, said switch in one position connecting said commutator in series with a portion of the transformer primary, and in another position cutting out 25 said commutator and cutting in a greater number of turns of said primary.

5. The combination with a source of alternating current, of a commutator and a rectifying switch driven in synchronism with said current, a transformer, a translating device, said commutator and a switch intervening between the primary of said transformer and said source, said switch in one position connecting said commutator in 35 series with a portion of the transformer primary, and in another position cutting out said commutator and cutting in a different number of turns of said primary, and an adjustable current restraining means in series 40 with said switch.

6. The combination with a source of alternating current, of a commutator and a rectifying switch driven in synchronism with said current, a transformer, a translating device, said commutator and a switch intervening between the primary of said transformer and said source, said switch in one position connecting said commutator in 45 series with a portion of the transformer primary, and in another position cutting out 50

said commutator and cutting in a different number of turns of said primary, an adjustable current restraining means in series with said switch, and a reversing switch in the primary circuit.

55

7. The combination with a source of alternating current, of a commutator driven in synchronism with the alternating current, a transformer, an X-ray tube connected in the secondary circuit of said transformer, and a switch in one position connected in 60 series with said commutator and the primary of said transformer and in another position connecting said transformer primary to said source of current independently of said commutator.

65

8. The combination with a source of alternating current, of a commutator driven in synchronism with the alternating current, a transformer, an X-ray tube connected in the secondary circuit of said transformer, a switch, said commutator and said switch intervening between the primary of said transformer and said source of current, said switch in one position connecting said 70 commutator in series with a portion of the transformer primary, and in another position cutting out said commutator and cutting in a different number of turns in said primary.

75

9. The combination with a source of alternating current, of a commutator driven in synchronism with the alternating current, a transformer, an X-ray tube connected in the secondary circuit of said transformer, a 80 switch, said commutator and said switch intervening between the primary of said transformer and said source of current, said switch in one position connecting said commutator in series with a portion of the transformer primary, and in another position cutting out said commutator and cutting in a greater number of turns of said primary.

85

10. In testimony whereof we have hereunto 90 affixed our signatures this 25th day of May, 1915.

HOMER C. SNOOK.
GEORGE H. WHITE.
